A CORPORATION OF NEW YORK

TELEVISION RECEPTION

Application filed September 17, 1928. Serial No. 206,360.

According to general practice the picture is transmitted electrically either by wire or radio and the transmitting circuit customarily includes a so-called photoelectric cell which is sensitive to light. This cell is subjected to pulsations of light derived sequentially from small areas of the object whose picture is to be transmitted. These pulsations of light are customarily produced by means of a disc having spirally arranged openings and rotated at a predetermined speed. Reproduction of the picture is accomplished by apparatus which includes a scanning disc rotated at the speed of the transmitting disc and having perforations which synchronize with perforations of the transmitter.

In the past it has been found difficult to maintain synchronism between the scanning disc of the reproducer or receiver and the scanning disc of the transmitter.

The main object of my present invention is to automatically synchronize the reproducer and the transmitter without requiring additional circuits or mechanical devices. To accomplish this with a maximum degree of simplicity and certainty I synchronize the receiving apparatus with the electrical impulses corresponding with the light impulses of the picture which is being received.

In the simplest form of apparatus for carrying out my invention I provide a synchronizing regulator whose armature is connected with the scanning disc of the reproducer.

This armature is provided with a series of pole pieces corresponding with the perforations in the scanning disc. The field coils of the regulator are connected in circuit with the lamp whose light furnishes the picture.

Fig. 1 is an edge view of the scanning disc and its regulator embodying my invention.

Fig. 2 is a diagram of a circuit of apparatus embodying my invention.

Fig. 3 is a face view of the preferred form of scanning disc.

Fig. 4 is a face view of a fragment of the armature.

Fig. 5 is a face view of a fragment of the field coils of the regulator.

Fig. 6 is a diagrammatic view showing the fluctuations of current flowing through the lamp.

Fig. 7 is a corresponding diagrammatic view illustrating the fluctuation of current in the output circuit of the amplifier and through the field coils while the disc is rotating.

The motor 10 may be of any suitable type and is designed so that it would normally tend to rotate at or near the speed of the transmitting disc.

The scanning member or disc 11 is of any suitable character preferably very thin and light in weight so that it will have a minimum inertia. This disc preferably has a series of perforations such as 12 arranged in two spirals as shown in Fig. 3 so that two pictures may be seen at all times. By locating the observation point properly one of these pictures may be selected or observed. This disc is mounted in a suitable manner on the shaft 13 and driven by the motor.

The motor shaft also carries an armature disc 14 having a series of radial bars 15 corresponding in number with the perforations in the scanning disc. This armature is preferably of iron, of high permeability, for instance, of silicon steel. The field coils 16 of the regulator are supported on the plate 17 which in turn is supported in a suitable manner from the motor casing or frame. These coils 16 are spaced apart circumferentially to correspond with the bars 15 above described. There may be a coil for each bar or one coil for every second, third, or fourth bar. The exact number of coils is not vital but the apparatus is more sensitive with a large number of coils.

In Fig. 2 as illustrated the field coils of the regulator are connected in a typical circuit including the tube 20 of the last stage of audio frequency amplification, the lamp 21 for instance being a neon lamp, and an amplifier tube 22 which is preferably interposed between the lamp and the regulator.

The fluctuations in the current through the lamp 21 occur somewhat as illustrated in Fig. 6. The zero or minimum current interval at 23, 24, 25, etc. correspond with the 100

time interval between the perforations in the transmitting disc.

It will thus be seen that the maximum synchronizing signal occurs only during the 5 interval between the perforations in the transmitting disc (not shown), in other words the synchronizing signal is independent of the picture signal. The picture signals are, of course, transmitted while the 10 perforations are in line or registry with the transmitting light source or optical image, and the synchronizing signal is transmitted during the interval between two successive 15 picture signals. In series with the neon lamp 15 is a small resistance 26 across the terminals of which is connected the amplifier tube 22, the plate circuit of which is connected to the field coils. The amplifier tube 22 is connected across this resistance in such a way that when 20 current is flowing through the neon lamp the grid of the amplifier tube 22 is charged negatively thus allowing only a small plate current to flow through the amplifier, but when the current through the neon lamp 21 is reduced to or near to zero at the points 23, 24, 25, etc. this negative charge on the grid of the amplifier 22 is removed and a large current flows through the plate circuit and the field coils thus energizing the latter. The 25 current flowing through the plate circuit of the amplifier and through the field coils is shown in Fig. 7 where a large pulsation of current takes place at the intervals 27, 28, and 29 corresponding to the no-current points 30 23, 24, and 25 respectively above described.

The result of this arrangement is that when the reproducing disc 11 is rotating in exact synchronism with the transmitting disc the maximum impulse points 27, 28, etc. occur 40 when the poles of the coils are opposite the bars 15 of the armature disc.

In case the speed of the transmitting disc increases or decreases the maximum current impulses in the lamp 21 will occur earlier 45 or later as the case may be thus producing a retarding or accelerating relation between the stationary field coils and the bars or arms 15 of the rotating armature attached to the reproducing disc 11. This in effect locks the 50 disc 11 in exact synchronism with the transmitting disc which will be maintained throughout a wide variation in speed of the transmitter disc due to the locking action of this device.

55 I claim:

1. In television receiving apparatus, a system for synchronizing the speed of a rotating armature with received signals, including a circuit having an element that passes substantially no current for less than a minimum applied voltage, means for impressing varying currents upon said circuit, means for periodically reducing the voltage applied to said element below said minimum, a resistor 60 in said circuit and means for applying a

drop of potential developed across said resistor to the input of a vacuum tube relay whereby for minimum current in said circuit maximum current is delivered by said tube, a magnetic system acting upon said armature, and means for applying said tube current to said system. 70

2. Television receiving and synchronizing circuits including a light producing element having a sharp increase of resistance when less than a definite potential is applied thereto, a resistor connected in series with said element, and a vacuum tube having its input circuit connected to said resistor, the polarity 75 of such connection being such that with normal current flowing through said first named circuit the input electrode of said tube is sufficiently negative to prevent substantial current from flowing in the output circuit of said tube. 80

3. In a television system an input circuit carrying picture and synchronizing signals, an output circuit coupled to said input circuit, and including an electro-optical translating device subject to said signals, said output circuit also including a coupling member, a phase inverting relay having its input circuit so connected to said coupling member that the bias produced by the picture signal alone causes the relay to become non-conductive, while the bias produced by the synchronizing signal allows the relay to become conductive, said relay having an output circuit including scanning control means actuated by the synchronizing signals in the output 90 circuit. 95

4. The method of operating a television system which comprises generating picture and synchronizing signals, amplifying said signals, passing said signals through a series 105 circuit containing an electro-optical device and a coupling member, causing the voltage generated by the picture signal alone in said coupling member to bias a phase inverting synchronizing relay to an inoperative condition, and causing the said relay to become operative by the voltage generated by the synchronizing signals. 110
